WITNESS:

Benj. Kahn

INVENTOR.

BY Fred E. Laird

Victor J. Evans

ATTORNEY.

UNITED STATES PATENT OFFICE.

FREDRICK E. LAIRD, OF TARRYTOWN, NEW YORK.

VALVE-ACTUATING MEANS.

Application filed December 2, 1919. Serial No. 341,948.

To all whom it may concern:

Be it known that I, FREDRICK E. LAIRD, a citizen of the United States, residing at Tarrytown, in the county of Westchester 5 and State of New York, have invented new and useful Improvements in Valve-Actuating Means, of which the following is a specification.

This invention relates to improvements 10 in valve controlling means and the principal object of the invention is to provide means for controlling the movement of the valve by fluid pressure or a vacuum.

Another object of the invention is to provide means whereby the device may be 15 adjusted to act under any desired pressure.

This invention also consists in certain other features of construction and in the combination and arrangement of the several 20 parts, to be hereinafter fully described, illustrated in the accompanying drawings and specifically pointed out in the appended claim.

In describing my invention in detail, 25 reference will be had to the accompanying drawings wherein like characters denote like or corresponding parts throughout the several views, and in which:—

Figure 1 is a sectional view of the 30 invention.

Figure 2 is a view of a modification.

In Figure 1, 1 indicates the valve casing in which is located a valve for controlling the supply of steam or other fluid to an 35 engine or the like. A frame 4 is located on said casing and the valve rod 2 of valve 2' projects into said frame. The upper part of this frame carries a ring shaped plate 5 and a cover plate 6 is bolted 40 to this plate 5 with a diaphragm 7 between the plates. Thus the cover plate and diaphragm forms a chamber 8. The cover plate is formed with an inlet port 9, which may be suitably connected with a steam 45 supply or other source of pressure so that the pressure will move the diaphragm. A rod 10 is connected with the said diaphragm and this rod passes through the guide 11 which forms part of the frame. The lower 50 end of the rod 10 is provided with a head 12 having a recess 13 therein and a wedge 14 thereon. A head 15 is carried by the valve rod 2 and this head is provided with a reduced extension 16 which fits in the 55 recess of the head 12. A lever 17 is pivoted

to have rocking movement in the frame 4 and the inner end of this lever is provided with a V-shaped recess 18 which is engaged by the wedge 14. A weight 19 is adjustably connected with the outer end of said lever 60 by the thumb bolt 20. A handle 21 is slidably mounted in the frame below lever 17 and this handle is pivotally connected with a slotted rod 22, one slot of which engages a pin 23 on the head 15 of the valve 65 rod. The inner part of lever 17 is slotted and a link 24 adjustably connects the lever with the rod 22, said link being connected with the said parts by the thumb bolts 25, which passes through the slots in the lever 70 and rod. The handle 21 may be held in adjusted position by means of a bolt 21^x.

It will be seen that the weighted lever tends to hold the diaphragm in its upper position but when the diaphragm is forced 75 downwardly by the pressure within the chamber 8 the weighted lever is rocked and thus movement is communicated to the valve rod by means of the link 24 and the rod 22. By moving the handle 21 the 80 fulcrum point of lever 22 is changed and thus the movements of the parts are increased or diminished and the amount of movement of the valve made more or less.

In the modification shown in Figure 2 85 the diaphragm is actuated by a vacuum instead of pressure so that rod 10' moved upwardly instead of downwardly so in order to communicate this movement to the valve I locate the fulcrum point of rod 22' 90 to the opposite side of link 24' from that shown in the first figure so that as the rod 10' and weighted lever 17' moves upwardly the pin 23' and valve stem will move downwardly. The handle 21' is provided 95 with an upwardly extending part 20^x which carries the pivot pin 21''. In other respects this arrangement of parts is similar to that above described.

From the above it will be apparent that 100 a valve for controlling a pipeline can be adjusted in relation to its seat by fluid under pressure introduced into chamber 8 or by a vacuum produced in said chamber. My invention can be used for maintaining a constant supply of steam to an engine by connecting the chamber 8 with the boiler or other source of steam supply which furnishes steam to the engine. If the pressure 105 in the boiler should increase the increased 110

pressure in chamber 8 would act upon the parts to move the valve to reduce the supply of steam to the engine. Of course the chamber 8 can be connected with a separate source of supply so that the valve could be actuated from this separate source.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A governor of the character described comprising a frame, a pressure chamber formed at the upper end of the frame and being adapted to be connected with a fluid supply, a diaphragm disposed in said chamber,

a rod depending from the diaphragm, a weighted pivoted rocking lever engaging said rod and being slotted adjacent its engaging end, a controlling valve arranged in a casing disposed at the lower end of the frame, a rod rising from the valve and being associated with the depending rod, a handle arranged for longitudinal movement through the frame and disposed in parallelism with the rocking lever, a rod pivotally secured to the inner end of the handle and being provided with a pair of spaced elongated openings, a pin projecting from the valve rod and engaging the adjacent slot of the last mentioned rod and a link adjustably connecting the slotted rod with the rocking lever as and for the purpose specified.

In testimony whereof I affix my signature.

FREDRICK E. LAIRD.
